(57) **CLAIM**

The ornamental design for a “tool storage backpack,” as shown and described.

DESCRIPTION

FIG. 1 is a perspective view;

FIG. 2 is a front view;

FIG. 3 is a back view;

FIG. 4 is a right view;

FIG. 5 is a left view;

FIG. 6 is a top view; and,

FIG. 7 is a bottom view.

The broken lines in the figures are for the purpose of illustrating stitching and portions of the tool storage backpack and form no part of the claim.
